(57) **CLAIM**

The ornamental design for a round sink, as shown and described.

DESCRIPTION

FIG. 1 is a top perspective view of a round sink embodying my new design;

FIG. 2 is a side plan view thereof, the front, back, left and right sides having the same image; and,

FIG. 3 is a top plan view thereof.

The broken lines shown in the drawings represent a hole in the sink and form no part of the claimed design.

1 Claim, 3 Drawing Sheets

FIG. 1

FIG. 2

FIG. 3
